UNITED STATES PATENT OFFICE.

ROBERT T. HAZELTON AND WILLIAM H. VOCKELL, OF CINCINNATI, OHIO, ASSIGNEES TO THE CINCINNATI MILLING MACHINE COMPANY, OF CINCINNATI, OHIO, A CORPORATION OF OHIO.

SLOTTING-CUTTER.

1,250,869.

Specification of Letters Patent. Patented Dec. 18, 1917.

Application filed May 22, 1915. Serial No. 29,709.

To all whom it may concern:

Be it known that we, ROBERT T. HAZELTON and WILLIAM H. VOCKELL, citizens of the United States, and residing at Cincinnati, 5 in the county of Hamilton and State of Ohio, have invented a new and Improved Slotting-Cutter, of which the following specification is a full disclosure.

This invention relates to rotary cutters of 10 a relatively heavy or massive construction, constituting a so-called milling cutter, and it deals more especially with a rotary dual-faced cutter applicable more especially for cutting slots by a straight-away operation.

15 Among objects of this invention may be enumerated—(A) to provide an “inserted tooth” construction which will embody all or many of the features of conventional cutters; (B) to provide for the employment of 20 lengths of “stock bar” material for constituting the inserted teeth; (C) to provide for a rear bracing or reinforcement of the projecting portions of the inserted teeth; and (D) to provide a very simple yet positive 25 and efficient interlocking arrangement whereby the various teeth may be adjusted for wear and fixed effectively in position.

Other objects will be in part obvious from the annexed drawings and in part indicated 30 in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features 40 thereof that they may embody the same by the numerous modifications in structure and relation contemplated by this invention, drawings depicting a preferred form have been annexed, as a part of this disclosure, 45 and in such drawings, like characters of reference denote corresponding parts throughout all the views, of which:—

Figure 1 is a side elevation of a construction of the inserted tooth type embodying 50 all of the tooth formation features with the added advantages of adjustability and replacement. Fig. 2 is a development in a plane of the periphery of the cutter shown in Fig. 1. Fig. 3 is a section developed in a 55 flat plane showing the method of fixing the

inserted teeth in place. Fig. 4 is a side elevation, partly in section, of the milling cutter shown by Fig. 1. Fig. 5 is a perspective of a detached isolated insertible tooth. Fig. 6 is a perspective of an isolated tooth retaining, tapering, interlocking wedge or cotter.

The construction embodies a body or holder portion A, preferably made of one-piece suitably contoured and having the usual arbor aperture and key-way whereby 60 it may be secured to a rotary spindle. This holder or body A provides a series of symmetrically arranged sockets 6, 7, 8, 9, etc.; the sockets 6 and 8 having their inner ends terminating at one side of the median 65 plane of the cutter and the sockets 7 and 9 having their narrow ends terminating at the other side of said plane, and these sockets preferably having their outer ends terminating more or less approximately in circumferential alinement as shown best by 70 Figs. 2 and 4. These sockets also extend at an angle to the radial or axial plane of the cutter as shown best by Fig. 1. Rearward of the outer ends of each socket, there is an 75 upstanding lug or projection 10, which is preferably integral with the body portion A, and which is formed to back or reinforce the teeth as shown.

The teeth are preferably made from short 80 lengths of round stock, and in a preferred embodiment of this invention are fashioned 85 as shown by Fig. 5 to provide a flat face 11 adapted to co-act with a flat sided taper pin or cotter whereby the tooth may be retained 90 rigidly in place.

As a further refinement this invention 95 preferably provides the flat face 11 with a multiplicity of serrations 12 having their grooves or ridges extending in parallelism transversely to the longitudinal axis of the insertible tooth. This tooth B also has its outer extremity configurated to embody the various clearance angles already discussed and it is seated in the sockets 6, 7, etc., as 100 shown by Figs. 1, 3 and 4. Extending transversely to each of the sockets 6, 7, etc., are sockets x, y, z, etc., adapted to receive the locating pins C, which, in this instance, are shown cylindrical and of uniform size from 105 end to end and are provided with inclined faces t which are fluted or serrated parallel with the plane of the face t, as indicated by 13. When these pins are driven home, as indicated by Fig. 3, the serrations 12 and 13 110

interfit, and not only wedge the teeth B firmly in place, but also provide a positive means for preventing these teeth from slipping lengthwise of their sockets.

5. Without further analysis, the foregoing will so fully reveal the gist of this invention that others can by applying current knowledge readily adapt it for various applications without omitting certain features that, 10 from the standpoint of the prior art, fairly constitute essential characteristics of the generic or specific aspects of this invention, and therefore such adaptations should and are intended to be comprehended within the 15 meaning and range of equivalency of the following claims.

Having thus revealed this invention, we claim as new and desire to secure the following combinations of steps and elements, 20 or equivalents thereof, by Letters Patent of the United States:—

1. A milling cutter combining a body portion having a plurality of outwardly extending sockets, an insertible tooth arranged 25 in each socket and providing serrations extending transversely to its length; and a locating pin having a serrated face extending at an angle and adapted to be wedged transversely to one of said insertible teeth 30 to hold the same against longitudinal displacement.

2. A metal-cutting tool combining an insertible cutter; a holder therefor having a socket conforming to and adapted to receive 35 the shank portion of said cutter, said holder also having a cylindric socket extending transversely to and intersecting said shank-receiving socket; and a substantially cylindric cotter adapted to go into said cylindric socket to engage said shank portion, said cotter having a plurality of closely related ribs extending at a slight angle to its longitudinal axis, and said shank portion having a series of ribs similar to those of 40 said cotter and extending at an angle to the axis of said shank portion, said ribs of said cotter being adapted to move endwise into coöperative interlocking relation with some of said ribs of said shank portion.

3. A milling cutter combining a body portion having a plurality of sockets extending outwardly and arranged in staggered relation with their inner ends alternately on opposite sides of the central plane and their 45 outer ends cut by said plane; and a tooth inserted in each socket.

4. A milling cutter combining a body portion having a plurality of staggered out-

wardly extending sockets, an insertible tooth arranged non-radially in each socket 60 and providing serrations extending transversely to its length; and a locating pin having a serrated face extending at other than a right-angle with said tooth and adapted to be wedged transversely to one of 65 said insertible teeth to hold the same against longitudinal displacement.

5. A metal-cutting tool combining a body-portion providing two sockets intersecting at other than a right angle; an insertible 70 tooth located in one of said sockets and having a flattened serrated face; and a pin located in the other socket and also having a flattened face having serrations inclined at an angle to the axis of the pin. 75

6. A metal-cutting-tool combining a body portion providing two sockets intersecting in offset relation with one another; an insertible tooth located in one of said sockets and having a flattened face provided with 80 serrations extending transversely to its longitudinal axis; and a pin located in the other socket and also having a flattened face extending longitudinally at a slight angle with the axis of said pin, said face being 85 provided with longitudinal serrations adapted to interlock with the transverse serrations of said insertible tooth.

7. In combination, a metal-cutting tool having a shank-portion, a holder therefor 90 having a socket conforming to and adapted to receive said shank portion, said holder having a cylindric socket extending substantially at right angles to, and intersecting, said shank-receiving socket, and a sub- 95 stantially cylindric cotter adapted to go into said cylindric socket and engage said shank-portion, said cotter having a plurality of closely related ribs extending at a slight angle to its axis, and said shank-portion 100 having a series of ribs similar to those of said cotter and extending substantially at right angles to the axis of said shank-portion, said ribs of said cotter being adapted to move endwise into coöperative interlocking 105 relation with some of said ribs of said shank-portion.

In witness whereof, we hereunto subscribe our names as attested by the two subscribing witnesses.

ROBERT T. HAZELTON.
WILLIAM H. VOCKELL.
